No. 13,433

NOV 14, 1882

Fig. 1.

Fig. 2

UNITED STATES PATENT OFFICE.

JOHN L. POPE, OF CLEVELAND, OHIO.

DESIGN FOR A SPRING AND AXLE BLOCK.

SPECIFICATION forming part of Design No. 13,433, dated November 14, 1882.

Application filed August 24, 1882. Term of patent 14 years.

To all whom it may concern:

Be it known that I, JOHN L. POPE, of Cleveland, in the county of Cuyahoga and State of Ohio, have invented and produced a new and original Design for Spring and Axle Blocks, of which the following is a specification, reference being had to the accompanying engravings, forming part thereof.

My invention relates to a novel design for spring and axle blocks, (used on vehicles;) and it consists in various improvements in the contour of the article, as will be hereinafter more particularly described, and set forth in the claims.

15 In the accompanying engravings, Figure 1 is a partial perspective, showing the top and sides of the article; and Fig. 2 is a similar view, showing the bottom and a side of the thing.

20 Looking at Fig. 1, it will be seen that the ends of the blocks are pointed arch shape, as at *a a*, and from the sides extend leaves or wings *b*, pointed at their outer ends, and each formed with a central rib, *c*. On each side, 25 near the ends of the block, are two perforated lugs or ears, *e e*.

Viewing Fig. 2 now, it will be observed that

the ends *a a* are tapered on what is the bottom or under side of the block. Starting from the ear-pieces *e*, the metal is curved to the points *x x*, and hollowed out or concaved on each side, producing a central rib or projection, *m*. Ornamental pieces *n* extend around and conform in contour to the under side of the wings or leaves *b*.

35

I claim as my new design and desire to secure by Letters Patent—

1. A spring and axle block with pointed arch ends, side wings, *b*, and lugs *e e e e*.
2. A spring and axle block with tapering ends and body curved and hollowed out upon the bottom, as shown.

3. The top of a spring and axle block, as shown.
4. The bottom of a spring and axle block, as shown.

5. The leaves *b*, ornamented, as shown at *n*.
In testimony whereof I have hereunto set my hand this 5th day of August, 1882.

JOHN L. POPE.

In presence of—
J. R. CURRIER,
J. M. ODELL.
